UNITED STATES PATENT OFFICE.

JOHN WILSON OROCK, OF MONTREAL, QUEBEC, CANADA.

MILL-TYPE DOOR.

Application filed December 18, 1926. Serial No. 155,616.

This invention relates to doors, and more particularly to a heavy duty door adapted for use in mills, warehouses and other places requiring large doors.

5 A primary object of the invention is to provide a door of the character set forth including a metal frame carrying therewith a non-metallic filler, the said frame being a rigid self-sustaining structure and serving as a base for attachment of hinges, hangers and door supports. In that connection it is proposed to provide a construction wherein the door and its supports provide a metal to metal contact when hung, in 10 contrast with the usual metal to wood construction.

Another object of the invention is to provide a construction wherein no strain whatever is imposed on any of the wood members, the weight being carried by the metal frame to which the hangers or hinges are attached, and therefore the door, when hung, will not sag, warp and pull apart as is frequently the case with ordinary doors.

25 A further object of the invention is to provide a mill-type metal frame door that is much stronger than the ordinary wood door of the same size and consequently does not require as heavy hardware or supports; 30 takes up less room; is easier to handle, and can be housed snugger than the ordinary door.

With the above and other objects in view which will more readily appear as the nature 35 of the invention is better understood, the same consists in the novel construction, combination and arrangement of parts hereinafter more fully described, illustrated and claimed.

40 A preferred and practical embodiment of the invention is shown in the accompanying drawings in which—

Figure 1 is a perspective view of a door constructed in accordance with the present 45 invention.

Figure 2 is a horizontal sectional view taken on the line 2—2 of Figure 1.

Figure 3 is a detail perspective view of the metallic frame of the door.

50 Figure 4 is a view illustrating a modified type of door mounted on hinges.

Figure 5 is an enlarged detail sectional view taken on the line 5—5 of Figure 4.

Figure 6 is a detail sectional view taken on the line 6—6 of Figure 3.

55 Figure 7 is an enlarged fragmentary sectional view showing a modified form of vertical frame member.

Similar reference characters designate corresponding parts throughout the several 60 figures of the drawings.

As heretofore indicated, a distinctive feature of the invention is to provide an all metal door framing which carries the entire 65 weight of the door and thus relieves the non-metallic filler of any strain or pressure. Accordingly, as will be observed from Figures 1 and 3 it is proposed to provide a door including the rigid rectangular metal 70 frame work A and the non-metallic filler B which is preferably of stout wood strips of suitable cross-sectional form.

The metallic frame A includes in its organization, the side frame members 1 and 2 and the top and bottom frame members 75 3 and 4 respectively. These members preferably are made of metallic bars or strips of a reinforced cross-sectional shape, for example, a T-shape, channel or L-shape, as clearly shown in Figures 2, 3 and 6. In the 80 case of the members 1 and 2, the head of the T faces the outside, and the shank or web portion of the T faces inwardly toward the door opening. These members 1, 2, 3 and 85 4 are rigidly held in assembled relation by 5 which are of substantially triangular formation and have an offset flange portion 5^a for engaging with the top and bottom edges of the channel frame members 3 and 4 respectively at the 90 same time providing additional stiffening and reinforcement because of their flanged formation.

It will thus be apparent that the frame A 95 consists of structural metal shapes held rigidly in position by the reinforcing gusset or corner plates 5 thereby providing a rigid and stable rectangular frame for receiving the filler or panel B which preferably is made of interlocking tongue and groove 100 strips 6 nailed as indicated at x (Fig. 1) or otherwise fastened each to the other as

they are put in the frame. As shown in the drawings, the heads of the nails α for securing one strip in place are covered by the next adjacent strip so that all of the fastenings for the strips are completely concealed. The upper and lower cut edges of the wooden panel strips 6 snugly fit within the channel members 3 and 4 so as to be firmly secured at their ends as well as protected against the weather, and the shank or web portion of the vertical members 1 and 2 is clamped between the end members 6 arranged at the vertical marginal edges of the panel, as best seen in Figure 2.

15 Figure 7 of the drawings illustrates a modified form of vertical frame member 1^a which also is of channel formation like the members 3 and 4. In this form of construction the wooden strips may seat in the channel and are therefore secured and concealed at their edges.

Figures 4 and 5 of the drawings illustrate an embodiment of the invention as applied to doors of the hinged type. In this form of the invention, each door includes a metallic self-sustaining frame A' and the non-metallic filler or panel B'. The frame A' includes the vertical metal frame members 1^a and 2^a which are connected by the horizontal top 25 and bottom frame members 3^a and 4^a as well as the intermediate rail 7. In order to add stability to the frame, diagonal braces 8 are used at the inside of the panel or filler A'. Also, the horizontal and vertical frame 30 members of the door are connected by the triangular gusset plates 9 which reinforce the junctions of the horizontal and vertical frame members. In addition to reinforcing these frame members, as just indicated, the 35 gusset plates afford means for attaching the strip portions of the hinges 10 so that the door is adequately supported at the door opening.

The wooden panel or filler B' of the type 40 of door shown in Figures 4 and 5 of the drawings preferably corresponds to the panel or filler of the door construction shown in Figures 1 and 2 of the drawings. That is to say, the panel or filler B' preferably is 45 of the mill-type construction, the same consisting of relatively narrow wooden strips, usually of the tongue and groove type closely fitted and interlocked and nailed or otherwise secured each to the other as indicated by 50 the dotted lines X on Figures 4 and 5, and, at the margins of the door frame, fitting in the angles and against the webs of the frame irons or members 1 and 2. Inasmuch as the 55 type of door shown in Figures 4 and 5 of the drawings fits inside of the door opening, it is preferable to provide a substantial marginal wooden framing surrounding the metal door frame, the said wooden framing consisting of a plurality of relatively wide 60 wooden strips 11 secured each to the other by 65

nailing or otherwise as indicated at α , and fitted in the outer angles and against the webs of the frame irons or members 1 and 2.

In the form of invention shown in Figure 4 of the drawings there is suggested the feature of a wicket W which may be utilized for access through the large door when it is not necessary nor desired to employ the full door-opening for entrance or exit.

It will be readily apparent that both of the foregoing described constructions fulfill the distinctive object of providing the self-sustaining metallic frame (A or A') for carrying the full load or weight of the door without imposing any of the stress or strain on the wooden fillers. Thus the rigid frame affords convenient means for supporting the entire door through the medium of the hangers H in Figure 1 which shows a sliding type of door or on the hinges 10 in the 70 swinging type of door in Figures 4 and 5. This construction results in a much stronger door than an ordinary wooden door of the same size and also provides a slow burning structure which for all ordinary purposes is 75 practically fire safe. Furthermore, due to the combination of the metal frame and the hinges or hangers, an all-metal support is provided which does not sag or wear like the ordinary door wherein the hinges or 80 hangers are secured to the wood part of the door by bolts or screws. Thus, the present construction is to be distinguished from 85 wooden or other non-metallic doors which merely have metallic edge guards or the like and which depend for their anchorage 90 and support upon the wooden or non-metallic part of the door itself.

From the foregoing it now will have been observed that the door hanger members or the door hinge members are riveted or fastened directly to the metal frame work of the door, and particularly to the strong and well reinforced corner parts thereof. Thus, the door hanger or door hinge members are in effect an integral and rigid part of the frame, and where the said hangers or door hinge members are located, the metal frame is well and strongly reinforced. Consequently, the use of bolts is entirely dispensed with in securing the hangers or hinge parts to the door frame, and the combination provides hangers and hinges which are a part of the metal frame, being rigid therewith so that an all-metal support for the door is provided which does not sag or wear like the ordinary door where the hanger parts or the hinge parts are secured to wood by bolts or screws.

Without further description it is thought 125 that the features and advantages of the invention will be readily apparent to those skilled in the art, and it will of course be understood that changes in the form, proportion and minor details of construction 130

may be resorted to without departing from the spirit of the invention and scope of the appended claim.

I claim:—

5. A heavy-duty mill-type door comprising two component parts, namely, a self-sustaining rectangular metallic frame fabricated with structural metallic shapes having flat outer faces and gusset plates secured to said

faces and having offset flanges for engaging 10 the outer edges of the frame members at the top and bottom of the door, and a wooden filler arranged within and supported by said frame.

In testimony whereof I hereunto affix my 15 signature.

JOHN WILSON ORROCK.
